TOOL GRINDING APPARATUS

Edd C. Oliver, Adrian, Mich.; Genevieve R. Oliver, executrix of said Edd C. Oliver, deceased, assignor to Genevieve R. Oliver, Adrian, Mich.

Application March 22, 1946, Serial No. 656,330

5 Claims. (Cl. 51—97)

1

This invention relates to tool grinders and more particularly to means associated with a grinding machine for grinding or sharpening fluted tools.

The invention comprehends the provision of tool supporting and manipulating means arranged for adaptation with a grinding machine and especially arranged to configure or re-sharpen fluted tools having radial or axial relief, or both.

The invention embraces the provision of a tool supporting and manipulating means adapted for use with a grinding machine for configuring or re-sharpening tools such as taps, center drills, gear chamfering cutters and the like which are provided with backing or radial clearance or relief.

The invention has for an object the provision of a tool carrying means adaptable for use with a grinding machine for grinding tools having both radial and axial relief wherein the arrangement is adjustable to accommodate tools having various pointing angles or taper.

A further object of the invention resides in an arrangement for grinding taps or other tools having axial and radial relief which is adjustable to accommodate various angularities of taper and embodies an adjustable grinding wheel dressing means whereby the wheel may be dressed immediately prior to a grinding operation.

The invention further comprehends the provision of simple yet effective means for grinding radial clearance or backing upon multi-fluted tools embodying cam means for actuating the tool into engagement with the grinding wheel at the proper angularity and simultaneously effect rotation of the tool to successively grind the operative portions of the tool with the desired radial and axial relief.

Still another object of the invention resides in the provision of means for quickly and effectively adapting the arrangement of the invention to accommodate the mechanism for grinding tools having varying numbers of flutes.

Another object is the provision of means for dressing the grinding wheel in a zone in substantial alignment with the position occupied by the axis of the tool during grinding operations whereby a high degree of accuracy is obtained.

Another object is the provision of portable unitary mechanism for supporting fluted tools during grinding or sharpening operations which may be used with various types and kinds of grinding machines.

Further objects and advantages are within the scope of this invention such as relate to the arrangement, operation and function of the related elements of the structure, to various details of construction and to combinations of parts, elements per se, and to economies of manufac-

2

ture and numerous other features as will be apparent from a consideration of the specification and drawing of a form of the invention, which may be preferred, in which:

5 Figure 1 is a top plan view of a grinding machine illustrating the arrangement of my invention associated therewith;

Figure 2 is an elevational view of the arrangement of my invention shown in Figure 1;

10 Figure 3 is an enlarged elevational view of the tool supporting means, parts being broken away for purposes of illustration;

Figure 4 is a sectional view taken substantially on the line 4—4 of Figure 3;

15 Figure 5 is a vertical sectional view taken substantially on the line 5—5 of Figure 3;

Figure 6 is a horizontal sectional view taken substantially on the line 6—6 of Figure 3;

20 Figure 7 is a disassembled view illustrating elements of an eccentric or cam construction forming a part of the invention;

Figure 8 is a diagrammatic view illustrating an example of the locus of motion of the tool supporting means during grinding operations;

25 Figure 9 is a front view of the tool supporting means of my invention shown in Figure 3;

Figure 10 is a fragmentary side elevational view of the arrangement of my invention showing the same as utilized for grinding or sharpening a center drill;

30 Figure 11 is a view similar to Figure 10 showing the arrangement as utilized for grinding or sharpening a gear tooth chamfering cutter;

Figure 12 is a sectional view through the tool 35 actuating cam arrangement showing the method of adjustment;

Figure 13 is a detail sectional view taken substantially on the line 13—13 of Figure 6, and

40 Figure 14 is a sectional view through a tap to show radial relief.

While I have illustrated the arrangement of my invention as particularly adapted for grinding tools such as threading taps, center drills, gear chamfering cutters and the like, it is to be understood that I contemplate the use of my invention for sharpening, configuring or grinding any type of fluted instrumentalities with axial or radial relief.

Referring to the drawings in detail, I have 45 illustrated a portion of a grinding machine including a frame 10 upon which is supported a hollow housing or casing 11 in the interior of which is journaled a shaft (not shown). The shaft extends exteriorly of the casing 11 and 50 supports a grinding wheel 12, the peripheral shape or configuration of which depends upon the type or kind of tool to be operated upon. The rear end of the shaft is provided with a pulley 17 which is arranged to be driven by a belt 19 from 55 a motor or other source of power (not shown).

The grinding machine frame is formed with a vertically and revolvably adjustable post 26 having a projecting ledge 21 upon which is mounted a tang 22 forming a sliding bearing for supporting a platen or table 24. The ledge 21 is provided with a threaded portion (not shown) through which extends a threaded shaft 26. An unthreaded portion of shaft 26 extends through an opening in a boss 25 carried by the table 24 and is arranged whereby rotation of the shaft 26 moves the table 24 longitudinally of the tang or slide 22. Fixed to the end of the shaft 26 is a hand wheel 27 or other suitable manipulating means for rotating the shaft.

The table 24 is formed with a ledge or platform 29 upon which is adapted to be mounted a pedestal or pillow block 30, the lower face of a flange 31 thereof being provided with parallel grooves or keyways within which are disposed keys 32 secured to the member 30 by means of screws 33. The upper surface portion of ledge 29 is formed with a groove 34 adapted to slidably receive the keys 32 for permitting adjustment of the member 30 with respect to the ledge 29. The flange 31 is formed with U-shaped recesses or slots adapted to accommodate bolts 35 for fixedly securing member 30 to the ledge 29. Adjustment of the member 30 may be had by releasing the bolts 35 and sliding member 30 along the ledge 29, the member 30 being held in a linear path of movement by means of the keys engaging the grooves or keyways formed in the ledge 29.

Mounted upon the pedestal 30 is a bracket or support 37 which is integrally formed with a depending cylindrical post or tenon 38 which snugly yet slidably fits into a vertical bore formed in the pedestal. The upper portion of the pedestal 30 is formed with a vertical kerf and joining the portions of the pedestal adjacent the kerf is a clamping bolt 39. When the clamping bolt 39 is drawn up, the tenon or post 38 is securely clamped against relative movement in the pedestal or block 30. The upper portion of the pedestal 30 is provided with a circular flange or dial portion 40 bearing a series of indicia 41 calibrated to indicate degrees, and the bracket 37 is provided with an index 42 cooperating with the indicia 41 on the pedestal to determine the relative annular position of bracket 37 with respect to the pedestal. The bracket 37 is formed with a projecting ledge 43 supporting a block or abutment 44 which is formed with tenon 45 extending into an opening in ledge 43, a portion of the tenon 45 being threaded to receive a securing nut 46. The upper surface of the ledge 43 is formed with a key way or rectangular recess 47 into which fits the rectangular lower portion of the abutment 44. The key way serves to maintain the abutment 44 in a relatively fixed position.

The bracket 37 is formed with a pair of upwardly and outwardly extending spaced ear portions 51. Each of the ear portions 51 is bored and threaded to accommodate threaded members 52, each threaded member being formed at one end with a cone shaped configuration 53. Pivotally supported upon the cone shaped configurations 53 of member 52 is a cage or housing 55, the latter having cone shaped recesses to accommodate the pivot members 53. The members 52 are provided at their outer ends with transverse kerfs or slots 57 adapted to receive a suitable tool for adjusting the pivot points 53 to provide for proper pivotal action of the cage or housing 55 without lateral lost motion between the cage and the member 37. Nuts 56 are

threaded on to the members 52 arranged to lock the same in adjusted position.

The housing or cage 55 has an upper semi-cylindrical portion 60 above which is mounted a semi-cylindrical cap or portion 61, both portions 60 and 61 when assembled forming a cylindrical or hollow interior configuration arranged to accommodate a tubular member or sleeve 62. The portions 60 and 61 are respectively provided with laterally extending flanges 63 and 64 which are held together by means of securing bolts 65. Both of portions 60 and 61 are formed to provide a hollow configuration or chamber 67 to accommodate a spiral toothed gear 68, the gear wheel 68 having a hub 69 which is drilled and threaded to receive a set screw 70 which cooperates with a recess in the exterior wall of the sleeve 62 for the purpose of fixedly securing the gear 68 to the sleeve 62. The sleeve 62 is provided adjacent its forward end with an enlarged head portion 71 which rests in a suitable circular recess formed in the forward ends of portions 60 and 61. Surrounding the head portion 71 is an annular recess formed in portions 60 and 61 arranged to receive and accommodate sealing material 72.

The rear end portion of sleeve 62 is threaded as at 73 and is adapted to receive a securing collar 74 which may be adjusted to predetermine the clearance providing for rotation of the sleeve 62 without endwise lost motion. The collar 74 is adapted to be locked in adjusted position by means of a set screw 76. The sleeve 62 supports a means for carrying a tap, center drill, chamfer cutter or other tool which is to be ground or sharpened. Disposed within the forward interior portion of sleeve 62 is a tool carrying member 78 having a bore 80 and which is formed with three slots or kerfs 79 equally spaced to form a collet-like configuration or chuck. The interior wall 40 of the forward portion of sleeve 62 is tapered as at 80 and the exterior adjacent portion of the chuck or member 78 is reciprocally tapered as at 81 so that when the member 78 is drawn rearwardly the cooperating tapered surfaces act to force the jaw portions 82 of member 78, separated by the kerfs 79, into binding engagement with the shank S of the tap T or other tool which is to be ground. The sleeve 62 is bored throughout a portion of its length to a diameter slightly larger than that of the cylindrical portion of member 78 and is adapted to receive a tubular member or inner sleeve 83 which is provided at its outer end with a knurled manipulating knob 84. As shown in Figure 4, the rear portion of member 78 is formed with a threaded tenon portion 85 and the forward portion of sleeve 62 is interiorly threaded for cooperation with the threaded tenon 85 whereby rotation of the manipulating knob 84 in one direction will draw the member 78 rearwardly into tool clamping or securing position. The side wall of member 78 is provided with a comparatively short keyway 87 into which extends the head 88 of a pin 89 which is carried in an opening in the side wall of sleeve 62, the member 88 serving to provide for relative longitudinal movement of member 78 and preventing relative rotational movement between member 78 and sleeve 62.

Disposed beneath the sleeve 62 and arranged 70 at an angle with respect to the axis thereof is a shaft 92 which is mounted in cylindrical openings formed in bosses 93 and 94 as shown in Figure 6, boss 93 extending outwardly from the housing 55 while the boss 94 is formed integrally with 75 a cover plate 95 which encloses the rear of cage

55, and is secured thereto by means of suitable screws 96. The shaft 92 is secured in place by means of a set screw 97. Journaled for rotation upon the shaft 92 is a sleeve 98 having a reduced portion 99 formed adjacent one end and upon which is fixed a helical gear 100 which is in mesh with helical gear 68. The sleeve 98 is also provided with a portion 101 carrying three spur gears 102, 103 and 104 which are arranged in parallel juxtaposed relationship and are arranged to rotate with the sleeve 98 by means of a key 105, the key 105 also serving to fix gear 100 to the sleeve 98. The gears 102, 103 and 104 are of different diameters for the purpose of changing the relative speed of rotation of gear 100 as hereinafter explained.

The cage 55 is formed with a boss portion 107 and formed on cover 95 is a similarly shaped boss portion 108, both of which are provided with bores in aligned relation and adapted to receive a shaft 110. Mounted upon the shaft 110 are three gears 114, 115 and 116 which are spaced apart by means of washers or discs 117 and 118 and are in mesh with gears 102, 103 and 104 respectively. While the gears 114, 115 and 116 are journaled for relative rotation upon the shaft 110, my arrangement includes means for selectively establishing a driving relationship between any one of said gears and said shaft whereby rotation of shaft 110 may be transmitted to shaft 92 to rotate the latter at three different speeds depending upon which of the gears 114, 115 and 116 is in driving connection to rotate with shaft 110. To attain the selective driving connection, the shaft 110 is formed with a slot or recess 119 within which is disposed a latch member 120 which is pivotally supported upon a pivot pin 121, the latter being disposed transversely in a bore in shaft 110. As particularly shown in Figures 6 and 13, a latch member 120 is provided with a projecting tooth or detent 122 which is arranged to extend into and cooperate with keyways 123 formed in each of the gears 114, 115 and 116. A substantial portion of shaft 110 is axially bored to receive a plunger 125. The plunger 125 has a central axial opening in which is disposed an expansive coil spring 127 and a tenon 128 having a rectangularly shaped head 129. The outer portion of the bore in the plunger 125 is threaded to receive a screw plug 130, the screw plug 130 serving as an abutment or reaction member for the spring 127. The spring 127 serves to urge the head 129 of plunger 128 into engagement with the latch pawl 120. The latch pawl 120 is formed with an end surface 131 of such configuration that when the pawl 122 is in engagement with a spline or groove in one of the gears 114, 115 and 116, the spring 127 resiliently urges the pawl 122 into selective operative connection with the gear in registration therewith. The discs 117 and 118 disposed at either side of the centrally positioned gear 115 function to move the pawl 122 out of the keyway or recess of a particular gear when it is desired to shift the pawl to a different gear and to prevent inadvertent disengagement of the pawl from the gear with which it is connected. For example, as viewed in Figure 6, the pawl is in engagement with the recess 123 in gear 116, and if it is desired to connect shaft 110 with gear 115 the operator grasps the knob 126 of plunger 125 and draws the same outwardly together with the parts carried thereby including the latch member 120. When the pawl 122 contacts or engages the disc 118, such engagement slightly rotates the latching member 122 about

its pivot pin 121 against the action of the spring 127 whereby the pawl 122 slips past the disc 118. As soon as the pawl 122 has passed the disc 118, the expansive force of spring 127 acts through plunger 128 upon the latching member 120, urging the latter in a direction to move the pawl 122 into the recess 123 formed in gear 115. This engagement establishes an operative driving connection between shaft 110 and gear 115, and simultaneously eliminates the driving connection between gear 116 and shaft 110. By moving the knob 126 further outwardly, the pawl 122 may, in the manner above explained, be caused to override the disc 117 so that an operative driving connection may be established between shaft 110 and gear 114. Thus by means of the shiftable latching member 120, an effective driving connection may be selectively established between any one of gears 114, 115 and 116 and the shaft 110 to rotate the driven shaft 98, gear 100, gear 68 and the sleeve 62 at three different speeds for purposes to be hereinafter explained. Additional variant speeds may be obtained by increasing the number of intermediate gears.

25 Tools such as taps, center drills, chamfering tools and the like are provided with radial and axial relief and are formed with a plurality of longitudinally extending flutes to provide lands having cutting walls or edges. The multiple speeds provided for the sleeve 62 and the collet tool carrier are selectively employed to rotate tools having different numbers of flutes at different speeds, the operation of such mechanism being hereinafter explained.

30 35 In order to obtain combined or simultaneous axial and radial relief of the tapered portion of the tool, my invention provides for movement of the tool into engagement with the wheel at a particular angle at the same time that the tool and its carrier are rotated through the gearing arrangement hereinbefore described. While any suitable means may be employed for moving the tool into engagement with the grinding wheel, I utilize a cam and abutment means for moving the axis of the tool into the wheel as each land of the tool is being ground or re-sharpened. As particularly shown in Figures 6, 7 and 12, a cam or disc 135 of annular configuration surrounds the shaft 110 and is provided with a central bore 136 of larger diameter than a hub portion 137 formed upon a second disc or member 138. The member 138 provides a means for carrying or supporting the cam disc 135, the latter being eccentrically or diametrically adjustable about the axis 45 of member 138 and shaft 110. The disc 138 is formed with diametrically disposed rectangular recesses or slots 140 and disc 135 is formed with diametrically disposed axially extending lugs or ears 142 which are adapted to snugly yet slidably fit into the recesses 140 with clearance in a diametrical direction for adjustment. The lugs 142 are provided with threaded bores radially disposed with respect to the axis of shaft 110 and adapted to accommodate threaded members or screws 144. The bases or bottoms of the recesses 140 are respectively formed with depressions 145 which are adapted to receive the inner extremities of the screws 144. By manipulation of both of the screws 144, the disc 135 may be shifted diametrically eccentrically with respect to the disc 138 for purposes to be hereinafter explained. The disc 138 is keyed to the shaft 110 by means of a key 148 extending into a keyway 149 formed in the interior of the bore in disc 138, a set screw 70 75 152 serving to fixedly secure the disc 138 in place

to prevent endwise movement. The periphery or circumferential surface of the disc 135 engages the upper end surface 150 of the abutment member 44 as shown in Figures 3 and 5. The forward extremity of shaft 110 is provided with a tenon 155 upon which is mounted a manipulating means or hand wheel 153 which is fixed to rotate with the shaft 110 by means of key 154. An integral projection formed on tenon 155 is threaded to receive a securing nut 156 to hold the hand wheel 153 in position on the shaft. A thrust washer or disc bearing 157 is disposed between the hand wheel 153 and the boss 107, as shown in Figure 6, to provide durable bearing surfaces.

My arrangement is inclusive of means for truing the grinding wheel 12. The housing 55 is provided with an integral disc-like table portion 160 which is formed with a depending or downwardly extending boss portion 161, the table and boss portion being bored to accommodate the shaft 163 which is integrally formed and depends from a member 164, the latter being supported upon the table 160. The shaft 163 terminates in a threaded tenon 165 which is adapted to receive a nut 166 formed with a finger grip 167 to facilitate manipulation thereof in order to clamp the member 164 in fixed position with respect to the table portion 160. The member 164 has a circular disc-like portion 168, the periphery of the same being inscribed with a series of indicia 169 representing degrees of angular movement of the table about the axis of shaft 163. The axis of the shaft 163 intersects the axis through the axis of the pivot pins 53 which pivotally support the housing 55. Secured to the table portion 160 is an index or finger 170 which is adapted for cooperation with indicia on the movable disc 168 for pre-determining the proper angular position of the disc for purposes to be hereinafter explained.

Formed upon the disc 168 is a U-shaped portion including upwardly extending ears 172 which are provided with axially aligned threaded bores to respectively receive a shaft 173 and a shaft 174. As particularly shown in Figure 4, the adjacent ends of the shafts are cone-shaped to present pivot points for pivotally supporting a swingable lever 175, the points of shafts 173 and 174 defining an axis about which the lever 175 is adapted for pivotal movement. The shaft 173 is fixedly secured in position in one of the bosses 172 by means of a set screw 177, while the shaft 174 has a threaded portion adapted to receive a locking nut 178. The outer end of the lever 175 is provided with a laterally extending member 180 which forms a handle for manipulating the lever 175 about its pivotal supporting means. The lever or arm 175 is adapted to carry a grinding wheel truing device or diamond 182 mounted in a member 183, the latter being received in a suitable bore formed transversely in the arm 175, the truing diamond supporting member being held in fixed position by means of a clamping or set screw 185. The truing operation may be accomplished by swinging the arm 175 upwardly to bring the diamond 182 into contact with the grinding wheel.

The housing cap 61 is formed with a pair of upwardly extending ear portions 187 and disposed between the ear portions is an L-shaped member 188 which is pivotally supported by means of a pintle 189. The member 188 provides a means of properly positioning or indexing a tap or other tool to be ground in the collet or support 78. The extremity of member 188 is configured as shown in Figure 3 to the shape of a

thin vane-like portion 190, the parallel walls of which form locating or positioning means for the tool. One of the walls of vane 190 engages the wall of a flute in the tap or other tool when the same is of a right hand type, the other wall of the vane being adapted for engagement with the wall of a flute in a tool of the left hand type. By this means there is provided an arrangement for adapting my invention for grinding or shaping taps having either right or left hand threads. The arm 188 may be swung to a position out of use as shown in Figure 2 after a tool has been fixed in position in the collet chuck 78 and before a grinding operation is initiated.

Means are provided for predetermining an initial position of the rotatable sleeve 62 in order to affix a fluted tool in the collet 78 in a proper relationship to be rotated by the gearing in the casing and oscillated by the cam 135 for grinding the several lands of the tool. To this end the cap or housing 61 is provided with a boss 200 formed with a vertical bore adapted to receive an indexing or positioning pin 201, the upper end of which is provided with a manipulating knob 202. The lower end of the indexing pin 201 has a projecting rectangular pawl or detent 203 which is adapted for cooperation with a kerf or slot 204 formed in the peripheral wall portion of the sleeve 62 to predetermine a starting position for rotation of the sleeve 62.

Means are provided for holding the shaft 201 out of engagement with sleeve 62 during rotative movements of the latter. This means is inclusive of a pin 205 which extends transversely through the member 201. The upper face of the boss portion 200 is provided with two sets of diametrically opposed grooves or kerfs 206 and 207 disposed 90 degrees apart. The grooves 206 are of a depth to accommodate the pin 205 so as to lower the member 201 until the detent portion 203 thereof engages in the groove 204 to secure the sleeve 62 in fixed position for initial setting of the tap or tool preparatory to grinding operations. When rotation of sleeve 62 is to take place, the member 201 is elevated by means of the finger piece 202, and the assembly rotated through 90 degrees until the pin 205 is in registration with the shallow recesses 207 as shown in Figures 2 and 3. Engagement of pin 205 in the shallow recesses 207 elevates the detent 203 above sleeve 62 so that the latter is free to rotate.

The operation of the arrangement of my invention is as follows: When it is desired to grind or sharpen a tool as for example, a tap T, the tap is first fixed in a particular position in the collet or supporting means 78. The finger piece 84 is rotated by the operator in a direction whereby the collet member 78 is moved to its forward position with the jaws 82 sprung outwardly. This action permits the shank S of the tap T to enter the hollow interior or bore 90 contained in the collet member. The sleeve indexing member 202 is rotated so that the detent 203 will be in a position to fall into registration with the kerf 204 so as to properly index the sleeve 62. The hand wheel 153 is then rotated, and through the medium of the gearing contained in the housing 55, the sleeve 62 is rotated until the detent 203 engages in the kerf 204. The operator then swings the L-shaped member 188 from its out-of-use position as shown in Figures 1 and 2 to the tap locating position shown in Figure 3. The tap or tool T is then rotated by the operator until one wall of the land thereof, formed by the fluting in the tool, engages the projection or lo-

cating portion 190 of member 188. This engagement establishes or predetermines the position of the tap circumferentially in the collet 78 so as to establish a proper relationship between the tap and sleeve 62. The operator then grasps the finger piece 84 and rotates the same in a direction to thread the inner sleeve 83 onto the threaded end of the collet member 78, which action draws the jaws 82 of the collet member 78 tightly into engagement with the shank S of the tap T. The L-shaped member 118 is then swung to an out-of-use position as shown in Figures 1 and 2, and the indexing member 202 elevated to disengage the detent 203 from the kerf 204 in the periphery of sleeve 62. In elevated position, the member 202 is rotated so that the pin 205 rests in the shallow recesses 207 so as to maintain the detent 203 out of engagement with the sleeve 62. The foregoing operations position the tap in the support fixture.

The bracket 37 is adjusted by rotating the post 38 in the pedestal or support 30 to set the tap at the proper angle for engagement with the peripheral face of a grinding wheel 12 to secure the desired pointing angle or tool taper. The angular position of the bracket 37 and hence the tap supporting means may be determined by the indication provided by the indicia 41. After the proper angular relation is established, the bolt 39 may be drawn up to tightly clamp the post 38 in the pedestal 30.

To insure accuracy in grinding, it is desirable to dress or true the grinding wheel prior to the grinding operations. In accomplishing this operation, the bracket 164, pivotally supporting the lever 175 and carrying the dressing diamond 182, is adjusted about a vertical axis by shifting the post 163 in a bore in the boss member 161 carried by the housing 55, the angle of rotation being determined by the indicia in registration with the index member 170. By this means the wheel dressing tool may be adjusted for swivel movement about the axis of the pivot pins 173 and 174 so that the wheel may be dressed in the proper angle with respect to the position of the tap or other tool carried in the collet 78. After the bracket 164 carrying lever 175 is adjusted to the proper angle, the lever 175 is swung upwardly to bring the diamond point 182 into engagement with the peripheral face of the grinding wheel causing the latter to be abraded at the proper angle.

As the arrangement of my invention is adapted to grind both axial and radial or backing relief upon the tap or other tool, the cage or housing 55 and tap mounting means are arranged for movement about the axis of the pivot pins 53 to move the tap into contact with the wheel in an arcuate locus. This is necessary in order to obtain relief or backing off clearance for the lands of the tap as illustrated at R in Figure 14. After the wheel has been dressed in the manner above explained, the tap T and the mechanism hereinbefore described carried by the bracket 37 are arranged to be moved toward the wheel 12. This movement is obtained by rotation of the hand wheel 27. When the tap is brought in juxtaposition with the grinding wheel, the operator rotates the hand wheel 153 thus rotating the cam 135 and driving shaft 110. Rotation of shaft 110 will cause rotation of sleeve or bushing 98 at a speed dependent upon which of gears 114, 115 or 116 is connected to be driven by shaft 110 through the medium of the latch member 120 carrying the driving pawl 122. If the fluted tool or tap is

provided with four flutes, the gear 114 is connected by pawl 122 to be driven by shaft 110. This selective driving engagement is obtained by moving the latch member 120 by manipulating the knob 126 axially of the shaft 110. If the fluted tool is provided with three flutes, the gear 115 is connected by the pawl 122 to be driven by shaft 110, and if the tool is formed with two flutes the gear 116 is placed in driving connection with shaft 110. Thus the gear 110 will drive the gear 68 and hence the sleeve 62 and the tap carried by the collet 78 at a speed with respect to the cam 135 dependent upon the number of lands or flutes in the tool.

15 The amount or degree of radial and axial relief or clearance is dependent upon the amount of eccentricity or adjustment of cam 135 with respect to the axis of disc 138 and shaft 110. The amount of eccentricity of the cam or disc 135 20 determines the magnitude or amount of forward movement of the housing 55 about the supports 53. The degree of eccentricity of the cam may be regulated or varied, and hence the clearance or relief angle for the tap changed, by adjusting 25 the screws 144 carried by the projections 142 formed on the cam member 135. The oscillatory movement of the housing 55 about its pivotal axis is caused by rotation of cam 135 in engagement with the upper surface 150 of the abutment 30 44. The operator rotates the hand wheel 153, thus rotating the cam or eccentric 135, and with each elevational movement of the housing 55, a land of the tap is ground with radial relief or clearance as well as with axial relief, the tap 35 being continuously slowly rotated whenever hand wheel 153 is rotated. As the housing 55 recedes from the grinding wheel by pivotal movement in a counterclockwise direction with each descending cycle of the cam, as viewed in Figure 3, the 40 tap T being rotated continuously by rotation of the sleeve 62 is brought into position for the next succeeding land thereof to engage the grinding wheel. Upon the next successive oscillatory movement of housing 55 caused by the action of cam 45 135, the succeeding land of the tool is ground with radial clearance or relief. This cycle is repeated until all of the lands on the tool have been brought into engagement with the grinding wheel. Between each complete grinding of the 50 several lands of the tool, the entire grinding fixture may be readjusted by movement of the fixture support or table 24 toward the grinding wheel preparatory to repeating the cycle of 55 grinding operations for further grinding of the tap if the condition of the tap requires additional grinding.

Figure 8 illustrates diagrammatically the direction or locus of movement of the tool carrying means. The line AB in this figure represents 60 the axis of oscillation of the housing 55 through the pivot pins 53 and the line CD represents the axis of the tool when carried in the chuck 78 associated with the sleeve 62. The line OD represents the component or vector of movement of the tool toward or into the wheel and represents axial relief while the line HD represents the component of radial relief. The line OH is 65 the resultant component representing the compound movement of the tool into the wheel whereby combined axial and radial relief is obtained simultaneously. Thus it will be noted that the tool moves into the grinding wheel generally in a longitudinal direction, the tool continuously 70 rotating simultaneously with its movement into 75

the wheel whereby compound radial and axial relief is obtained simultaneously.

Figure 10 of the drawings illustrates the arrangement of my invention as used for grinding or sharpening center drill 210. It is to be noted that the grinding wheel 12' has a peripheral shape or configuration to produce the exterior contour of the center drill during grinding operations. The axial and radial relief is imparted to the center drill in the same manner that is utilized in obtaining the relief in a tap.

Figure 11 illustrates the arrangement of my invention as utilized for grinding a chamfering cutter 122 with both axial and radial relief. In grinding this type of tool it should be noted that the grinding wheel 12" is configurated so as to obtain the proper silhouette or exterior contour of the cutter.

While I have illustrated the arrangement of my invention as particularly adapted for imparting axial and radial relief to taps, center drills and chamfering tools, it is to be understood that I contemplate the use of the arrangement for any other type of tools wherein radial relief, axial relief or both are to be imparted to any tool or instrumentality. The fixture may be used with any suitable type of grinding machine, the drawings illustrating in part one form with which the fixture is particularly adaptable.

It is apparent that, within the scope of the invention, modifications and different arrangements may be made other than is herein disclosed, and the present disclosure is illustrative merely, the invention comprehending all variations thereof.

What I claim is:

1. In a tool grinding apparatus comprising in combination, a pedestal; a bracket associated with said pedestal and arranged for rotary adjustment with respect thereto; a housing pivotally supported upon said bracket and arranged for oscillation about the axis of said pivotal connection; a tool holder journaled for rotation upon said housing about an axis angularly disposed with respect to the axis of pivotal movement of the housing; means for rotating said tool holder relative to said housing; and means associated with said tool rotating means for causing oscillation of said housing about the axis of its pivotal support; and means for varying the number and amplitude of oscillations of said housing with respect to the rotational speed of said tool holder.

2. An apparatus for mounting tools during grinding operations comprising in combination, a support; a bracket revolvably mounted upon said support; means for locking said bracket in adjusted position upon said support; a housing mounted upon said bracket and arranged for relative oscillatory movement; a driving shaft journaled on a housing; a plurality of gears of different diameters mounted on said driving shaft; a member journaled on the housing; a plurality of gears mounted on said member and in enmeshment with the gears journaled on said driving shaft; a tool supporting member journaled upon said housing and arranged to be driven by said gearing about an axis angularly disposed with respect to the axis of oscillation of the housing, and means for establishing a selective driving connection between sets of said gears for varying the speed of said tool supporting member with respect to said driving shaft.

3. An apparatus for mounting tools during

grinding operations comprising, in combination, a support; a bracket revolvably mounted upon said support; means for locking said bracket in adjusted position upon said support; a housing mounted upon said bracket and arranged for relative oscillatory movement; a driving shaft journaled on the housing; a plurality of gears of different diameters loosely journaled on said driving shaft; a member journaled on the housing; a plurality of gears fixedly mounted on said member and in enmeshment with the gears journaled on said driving shaft; a tool supporting member journaled upon said housing about an axis angularly disposed with respect to the axis of oscillation of the housing and arranged to be driven by said gearing means for establishing a selective driving connection by said driving shaft and the gear journaled on said shaft for varying the speed of said tool supporting member with respect to said driving shaft.

4. In a tool grinding apparatus including in combination, a support; a bracket mounted on said support and arranged for rotary adjustment with respect thereto; a housing supported upon said bracket and arranged for oscillation about an axis; a tool holder journaled on said housing for rotation about an axis angularly disposed with respect to the axis of oscillation of the housing; means for rotating said tool holder; means associated with the tool holder rotating means for oscillating said housing about its axis; means for varying the amplitude of oscillatory movement of the housing, and means for varying the frequency of oscillations of the housing with respect to the rotational speed of the tool holder.

5. In a tool grinding apparatus including in combination, a support; a bracket mounted on said support and arranged for adjustment with respect thereto; a housing supported upon said bracket for oscillatory movement relative thereto; a tool holder journaled on said housing for rotation about an axis angularly disposed with respect to the direction of oscillation of said housing; means including gearing for rotating said tool holder; means associated with said tool holder rotating means for concomitantly oscillating said housing relative to the bracket; means for varying the amplitude of oscillatory movement of the housing, and means for varying the frequency of oscillations of the housing with respect to the rotational speed of the tool holder.

EDD C. OLIVER.
